wick, N. J., a corporation of New Jersey

Application February 19, 1942, Serial No. 431,519

9 Claims.

(Cl. 66—14)

My invention consists in the novel features hereinafter described, reference being had to the accompanying drawings which illustrate an embodiment of the same, selected by me for the purpose of illustration and the said invention is fully disclosed in the following description and claims.

My invention relates to circular knitting machines having coaxial superposed needle cylinders with selector mechanism for transferring selected needles from one cylinder to the other and pertains particularly to improvements in circular knitting machines of the kind described and claimed in co-pending application Serial No. 374,334, filed January 14, 1941.

In a circular knitting machine having coaxial superposed needle cylinders, the needles are actuated by sliders located in the needle slots of the upper and lower cylinders and provided with knitting butts acted upon by cams for actuating the needles to draw stitches and transfer butts acted upon by cams to effect the transfer of needles from one cylinder to the other. In order to carry out the desired operations, it is customary to provide butts of different lengths. For example, in an opposed cylinder machine for knitting men's hose, the sliders on one side of the lower cylinder corresponding to the needles producing the heel and toe pockets, are provided with short knitting butts and the sliders on the opposite side of the lower cylinder are provided with long knitting butts. The upper cylinder sliders corresponding to the short knitting butt lower cylinder sliders have long transfer butts and the upper cylinder sliders corresponding to long knitting butt lower cylinder sliders have short transfer butts. To produce an article of hosiery having the usual 1 x 1 rib knit top portion or having an anti-ravel edge requiring alternate needles in the upper cylinder, it has been customary to provide alternate lower cylinder sliders with long transfer butts and the intermediate lower cylinder sliders with short transfer butts in order that alternate needles may be transferred to the upper cylinder by a cam engaging the long transfer butts but not engaging the short transfer butts.

In accordance with the above mentioned application, Serial No. 374,334, provision is made for selectively transferring needles from one cylinder to the other by means of a plurality of separately controlled sets of selector levers acting on selectors associated with the needles and for by-passing selected lower cylinder needles at at least one feed of a multi-feed machine to produce fabrics and articles of novel design. The selective bypassing of lower cylinder needles is effected by cams acting on the transfer butts of the lower cylinder sliders; the said butts being made of different lengths to provide the desired selection. This use of the transfer butts of the lower cylinder sliders to by-pass selected needles to obtain a decorative design precludes their use for transferring alternate needles or groups of needles to the upper cylinder for the purpose of producing an anti-ravel edge or 1 x 1 or other rib knit fabric. It is hence necessary to control the selective transfer of needles from one cylinder to the other by means of the selector levers, one set of levers being used for each type of rib fabric or other patterns desired and separate control mechanism being provided for individually controlling each set of levers.

It is an object of the present invention to provide an improved knitting machine of simpler construction and operation. In accordance with my invention one set of selector levers is employed to obtain a plurality of different patterns or types of fabric. For example, in making a sock having a tubular welt or other anti-ravel structure requiring alternate needles in the upper cylinder, rib knit tops other than 1 x 1 rib, for example, a top formed of 2 x 2 rib fabric requiring a needle selection different from that required for the anti-ravel edge, and a Links-Links float thread leg portion, one set of selector levers is employed to produce the Links-Links leg portion and a single set of selector levers is employed to obtain both the 1 x 1 selection for the anti-ravel edge and the 2 x 2 or other selections required for the rib knit top portion. By thus making it possible to obtain with a single set of selector levers a plurality of different needle selections, each of which is maintained for a protracted period of time as for example, in producing a tubular welt or a rib knit top portion, the construction and operation of the machine is greatly simplified, making the machine less expensive to build and easier to keep in proper running order. As machines of the opposed cylinder type are at best rather complicated, the simplification achieved by the present invention represents a distinct advance in the art.

The objects and advantages of the invention will be more fully understood from the following description of an embodiment thereof shown by way of example in the accompanying drawings, in which

Fig. 1 is a front elevation of a portion of a knitting machine in accordance with the invention, certain details being omitted for the sake of clearness.

Fig. 2 is a schematic elevational view showing mechanism for operating shunt cams in the upper and lower cylinder cam blocks.

Fig. 3 is a schematic elevational view showing mechanism for operating a selecting cam in the lower cylinder cam block.

Figs. 4 and 5 are horizontal sectional views taken on the lines 4—4 and 5—5 in Fig. 1 showing the operation and control of selector levers.

Fig. 6 is a detailed perspective view of a portion of the mechanism shown in Figs. 4 and 5.

Fig. 7 is an enlarged front elevational view showing a portion of the mechanism operating and controlling the selector pattern drum appearing near the top of Fig. 1.

Fig. 8 is a horizontal sectional view taken on the line 8—8 in Fig. 7.

Fig. 9 is a fragmentary top plan view of the machine with portions broken away.

Figs. 10, 11, 12 and 13 are horizontal sectional views taken on the lines 10—10, 11—11, 12—12 and 13—13 in Fig. 7.

Fig. 14 is a vertical sectional view on the line 14—14 in Fig. 9.

Figs. 15a and 15b are fragmentary views showing alternative cam arrangements.

Fig. 16 is a view similar to Fig. 15 showing alternate pairs of needles in the upper cylinder for producing 2 x 2 rib fabric.

Fig. 17 is a view similar to the upper part of Fig. 15 showing an arrangement of selector butts for producing the article of hosiery illustrated in Fig. 19.

Fig. 18 is a view similar to Fig. 15 showing the production of Links-Links float thread fabric.

Fig. 19 is a side view of an article of hosiery produced in accordance with my invention.

Fig. 20 shows diagrammatically a section of the leg portion of the sock shown in Fig. 19.

In Figs. 1 to 18 of the drawings, there is shown so much of a knitting machine as is necessary to illustrate the present invention. With reference particularly to Figs. 1 and 15, the numeral 20 represents the lower knitting cylinder provided with vertically movable sliders 21, located in the grooves thereof, and having transfer butts 22 and knitting butts 23 for engaging suitable cams on the cam ring indicated at 24, each of the sliders 21 being provided at its upper end with a terminal portion comprising a needle engaging hook 25 and a latch engaging extension 26 for connecting the sliders with such needles as are present in the lower needle cylinder. The transfer butts 22 on the sliders 21 are utilized for transferring needles to the upper cylinder and may also be used for effecting a needle selection in the lower cylinder. If the transfer butts are to be used for a needle selection, they are made of different lengths to obtain the selection desired. Knitting butts 23 of sliders 21 may also be of different lengths. Ordinarily, consecutive sliders constituting approximating one-half the circular series thereof will have short knitting butts for operating the needles during reciprocating work in knitting the heel and toe pockets, while the remaining sliders will have long knitting butts. A greater number of different lengths of knitting butts may be provided if desired.

The upper needle cylinder 30 is provided with a series of sliders 31 engaging the grooves thereof and having transfer butts 32 and knitting butts 33 for engaging cams in the upper cam ring 34. The sliders of the upper cylinder are each provided at their lower ends with a terminal portion comprising a needle engaging hook 35, and a latch engaging extension 36 for engaging the upper ends of the needles when they are transferred to the upper cylinder. The trans-

fer butts 32 of the sliders in the upper cylinder are ordinarily of different lengths, short transfer butts being provided over the long knitting butts in the lower cylinder and long transfer butts being provided in the upper cylinder over the short knitting butts in the lower cylinder.

The needles indicated at 40 are each provided with the usual hooks 41 and latch at each end. When the needles are in the lower cylinder, their lower hooks will engage the hooks 25 of the corresponding sliders 21 and the extensions 26 will engage the lower latches so that the needles will be operated by and with the sliders 21. When all of the needles 40 are in the lower cylinder, the machine produces plain knitting. For the production of rib knitting, certain of the needles will be transferred to the upper cylinder, whereupon their upper hooks will engage with the hooks 35 of the upper cylinder sliders 31 so that the needles will be actuated by the upper sliders.

If the rib knit fabric is to have continuous vertical ribs, the same needles will be operated in the upper cylinder throughout the knitting of the fabric. If it is desired to produce Links-Links fabric, the needles are transferred back and forth from one cylinder to the other in predetermined sequence, so that certain needles operate at times in the upper cylinder and at the other times in the lower cylinder. This re-

sults in the wales produced by these needles being composed partly of inwardly facing stitches produced by operation of the needles in the upper cylinder, and partly of outwardly facing stitches produced by operation of the needles in the lower cylinder.

In certain of the operations herein-after described, the desired distribution of needles between the upper and lower cylinders is effected by transferring all of the needles to the upper cylinder and retransferring selected ones of the needles back to the lower cylinder. Where refer-

ence is made in the description and claims to the transfer of needles from one cylinder to another, the expression designates the net result of the transferring operation unless otherwise appears from the context.

The upper needle cylinder is provided with an extension 42 having vertically movable selectors 43 located in grooves which form continuations of the grooves in the upper needle cylinder (Figs. 1 and 15). Each of the selectors 43 has a leveling butt 43a for bringing all of the selectors to the same level and one or more selector butts 43b. The selector butts 43b are disposed at different levels, certain selectors having butts at one or more levels and other selectors having butts at other levels.

In the arrangement illustrated in the drawings (Fig. 15) there are twelve selector butts positioned, numbered 1 to 12 respectively. It will be understood that none of the selectors 43 will ordinarily have selector butts at all twelve levels, but each selector may have one or more butts at any of the levels desired. The selector butts are adapted to be engaged by selector levers arranged at corresponding levels as described more fully below to depress the selected ones of the selectors, and through engagement of the lower end of the selectors with the upper end of the sliders depress corresponding sliders to effect the transfer of corresponding needles from the upper to the lower cylinder.

The machine in accordance with the invention is provided with a plurality of thread feeding stations, two such stations being illustrated in the drawings. At each of the feeding stations there

are provided suitable thread guides for feeding the thread to the needles, and suitable tension devices for applying tension to the thread. There will ordinarily be a plurality of thread guides and a corresponding number of tension devices at each feeding station, but for the sake of simplicity each station is represented in the drawings by a single thread guide indicated by a dot in Figs. 15, 16 and 18, one of the feeding stations hereinafter referred to as the main feeding station being represented by a thread guide 44 and a second feeding station being represented by a thread guide 46. Suitable mechanism is provided for moving the feed fingers into and out of feeding position.

At the main feeding station the needles in the lower cylinder are manipulated by a center cam 48 and a main stitch cam 49 adapted to engage the knitting butts 23 of the sliders 21. The stitch cam 49 is movable in a vertical direction to regulate the length of stitch drawn by the needle. A similar stitch cam 51 is provided for knitting in a reverse direction when the needle cylinder is reciprocated, as in the formation of the heel and toe pocket. The direction of movement of the needles relative to the cam blocks in continuous circular knitting is indicated by the arrow at the top of Fig. 15. Following the main feeding station there is provided a stationary clearing cam 52 by-passed by a race-way 53. The passage of the knitting butts 23 of the sliders 21 through the race-way 53 is controlled by a shunt cam 54 movable into and out of operative position. When the shunt cam 54 is in operative position, the knitting butts 23 ride up the cam and up the space of cam 52, thereby raising the needles to clearing position, i. e., a position in which the previously drawn stitch is placed below the latch of the needle so that it will be cast off when the needle is again drawn down. When the shunt cam 54 is in inoperative position, the knitting butts 23 are by-passed through the race-way 53, so that the needles are not raised to clearing position, and the previously drawn stitches are retained on or above the latches of the needles.

The movement of the shunt cam 54 into and out of operative position is controlled by a two-step cam 55 on cam drum 56 on the main pattern shaft 57 by the mechanism shown in Figs. 1 and 2. In the arrangement illustrated, the shunt cam 54 is provided with a rearwardly extending projection 54a which is pivotally connected to a short arm 58, pivoted at its lower end to a bracket 59, provided on the lower cam ring 24. The upper end of the arm 58 is suitably connected, for example, by a Bowden cable 60, to a cam follower 61 adapted to engage the control cam 55. A compression spring 62 acting on the upper end of the pivoted arm 58 tends to move the shunt cam 54 radially inwardly to its operative position. When the cam follower 61 rides up on cam 55 of cam drum 56, the upper end of the pivoted arm 58 is pulled outwardly against the action of spring 62 to withdraw the shunt cam 54 to inoperative position.

The by-passing of knitting butts 23 of sliders 21 through the race-way 53 (Fig. 15) is further controlled by a selecting cam 63 which in the arrangement shown, is located approximately below the shunt cam 54 and is adapted to engage the transfer butts 22 of the sliders. In order to obtain a needle selection, the transfer butts 22 of sliders 21 are of different lengths so that the selecting cam 63 will engage the transfer butts 75

of certain sliders only. The transfer butts that engage selecting cam 63 will ride up the face of the cam, thereby raising the sliders sufficiently to bring the knitting butts 23 of those sliders above the race-way 53 and into engagement with the clearing cam 52 whereby the needles will be raised to clearing position. Assuming that the shunt cam 54 is in inoperative position, the remaining sliders which are not engaged by selecting cam 63 will not be raised and their knitting butts will be by-passed through race-way 53. To obtain different needle selections or to obtain a needle selection around one portion only of the needle cylinder as for example in knitting the foot of a sock where it is desired to have a needle selection for the instep but not for the sole, the transfer butts 22 are made of at least three different lengths and the selecting cam 63 is radially movable so that it can be positioned to engage the long transfer butts only, or positioned to engage both the long and the medium transfer butts.

In the arrangement shown in the drawings, the radial movement of selecting cam 63 from one position to another is controlled from the main pattern shaft by the mechanism illustrated in Figs. 1 and 3. The selecting cam 63 is carried by a radially movable plunger 63a extending out through the cam ring 24 and having a transverse pin 63b which is acted upon by a spring 64 tending to move the cam 63 to its outer position. Means for moving the selecting cam 63 to its inner position against the action of spring 64 comprises a cam follower 65 pivoted to a suitable support 65a and having a cam engaging portion 65b adapted to engage a two-step cam 66 on cam drum 56. The cam follower 65 is connected for example by a link 67, a crank 68, a shaft 69, a crank 70 and a link 71 with a bell crank lever 72 pivoted at 72a to a suitable support on the frame of the machine. The free end 72b of the bell crank lever 72 bears against the outer end of plunger 63a which carries selecting cam 63. When the cam engaging portion 65b of the cam follower 65 rides up on the high cam portion 66 on cam drum 56, the free end of the bell crank lever 72 is moved inwardly (to the right in Fig. 3) pushing the cam 63 to its inner position. When the cam engaging portion of the cam follower 65 rides off of cam 66, the selecting cam 63 is moved to its outer position by the action of spring 64. The timing of the movement of the selecting cam will be explained in connection with the operation of the machine.

The shunt cam 54 and selecting cam 63 will ordinarily not be used at the same time. When the selecting cam 63 is being used, the shunt cam 54 will ordinarily be maintained in inoperative position so that the knitting butts of the sliders not raised by the selecting cam 63 will be by-passed through raceway 53. When it is desired to by-pass all of the knitting butts 23, the shunt cam 54 is maintained in inoperative position and the selecting cam 63 is disconnected so that it will not engage any of the transfer butts. When the shunt cam 54 is in its operative position, all of the knitting butts will be caused to ride up the face of the clearing cam 52, and the position of selecting cam 63 is hence immaterial. If desired, the selecting cam 63 may be made to move inwardly to engage all of the transfer butts so as to cause all of the knitting butts to ride up clearing cam 52, whereby the shunt cam 54 is rendered unnecessary.

At the second feeding station represented by

the feed guide 46 (Fig. 15), there are provided a draw down cam 73 and a stitch cam 74. The draw down cam 73 is movable radially into and out of operative position. The stitch cam 74 remains in operative position, but is adjustable vertically to regulate the length of the stitches drawn by the needles in the lower cylinder at the second feed. When the draw down cam 73 is in operative position, the knitting butts 23 of the sliders 21 which have been raised by clearing cam 52 ride down the face of cam 73 and continue down and under stitch cam 74 causing the needles to draw a stitch of the thread received at the second feeding station (Fig. 15). Knitting butts which are by-passed through the race-way 53 will be drawn down slightly by stitch cam 74 and pass underneath this cam (Fig. 18). It will be noted that when the knitting butts of the sliders are caused to ride up over clearing cam 52 either by reason of the engagement of the knitting butts with shunt cam 54, or engagement of the transfer butts with selecting cam 63, the corresponding needles in the lower cylinder are raised high enough to receive the thread fed at the second feeding station and will draw stitches of this thread when drawn down by cam 73 and stitch cam 74. When the knitting butts are by-passed through the race-way 53, the corresponding needles are kept so low that they do not receive thread fed at the second feeding station (Fig. 18) and retain the stitches of thread drawn at the main feeding station.

Beyond the draw down cam 73 and the stitch cam 74, there is provided a secondary clearing cam 75 for raising all of the needles to clearing position preparatory to receiving the thread fed at the main feeding station. The lower cam ring 24 is also provided with a transfer cam 76 adapted to engage transfer butts 22 of sliders 21 for transferring all or certain of the needles to the upper cylinder as is usual in the coaxial type of knitting machine. As the mechanism for operating the transfer cam may be of usual form, it will not be further described.

In Fig. 15b there is shown an alternative arrangement in which the single lower transfer cam of Fig. 15 is replaced by a transfer cam 76a and an associated swivel cam 76b. The transfer cam 76a is located so that the transfer butts of the lower cylinder sliders will ordinarily pass below it unless the sliders are raised by engagement of the knitting butts with the swivel cam 76b. To transfer needles to the upper cylinder, the lower transfer cam 76a is placed in operative position and the swivel cam 76b is then moved in against the short knitting butts so as to engage the first of the long knitting butts, whereupon the cam is moved further inwardly to engage the short knitting butts when again presented. The swivel cam raises the sliders insufficiently to effect transfer of the needles, but high enough for the transfer butts to be engaged by transfer cam 76a so that those needles having associated therewith transfer butts of sufficient length to be engaged by transfer cam 76a will be transferred to the upper cylinder. Where reference is made in the following description to the lower transfer cam, it will be understood that this may be either the single cam 76 of Fig. 15 or the transfer cam 76a and associated swivel cam 76b of Fig. 15b.

The upper cam ring 34 is provided adjacent the main feeding station 44 with a positioning cam 80 adapted to engage the knitting butts of the sliders in the upper cylinder to position the up-

per cylinder needles to receive thread fed at the main knitting station and a main stitch cam 81 adapted to engage the knitting butts of the sliders to cause the upper cylinder needles to draw stitches of the thread received. Following the main feeding station there is provided a descending cam 82 adapted to engage the knitting butts to move the sliders and associated needles downwardly. In the form of the invention shown in Fig. 15, cam 82 is of sufficient height to move the needles downwardly to clearing position and thus constitutes a clearing cam for the main feeding station. In the form shown in Fig. 16, cam 82 is cut off so that it does not move the needles to clearing position, and the needles hence retain the stitches drawn by stitch cam 81 at the main feeding station. Following the descending cam 82 there is provided a second positioning cam 83 for raising the needles to proper position to receive thread fed at the second feeding station 46. By-passing the descending cam 82 there is provided an upper race-way 84 for the knitting butts of the upper cylinder sliders. The passage of the knitting butts through race-way 84 is controlled by an upper shunt cam 85 which is adapted to engage the knitting butts of the sliders and is movable radially into and out of operative position. When the shunt cam 85 is in operative position, it blocks off the race-way 84 causing the knitting butts 33 to ride down the face of descending cam 82. When the shunt cam 85 is in inoperative position, the knitting butts pass through race-way 84. It will be seen (Fig. 16) that when shunt cam 85 is in operative position to cause the knitting butts to ride down the face of descending cam 82 and up cam 83, the needles are properly positioned to receive the thread fed at the second feeding station 46. When the upper shunt cam 85 is withdrawn, allowing the knitting butts to be by-passed through race-way 84, the needles are kept at a higher level so that they will not take the thread fed at the second feeding station, and will retain the stitches drawn at the main feeding station (Fig. 15).

Suitable mechanism is provided for moving the upper shunt cam 85 into and out of operative position, one arrangement of such mechanism being shown by way of example in Figs. 1 and 2. In the arrangement shown, the upper shunt cam 85 is carried on the inner end of a radially movable plunger 85a, which extends through a bushing 86 and has at its outer end a transverse pin 85b. A spring 85c tends to move the shunt cam inwardly to operative position. The outer end of the plunger 85a is straddled by a bifurcated cam block 87 carried by a vertically movable spindle 87a, and having inclined cam surfaces engaging the transverse pin 85b. A spring 87b tends to move the cam block and spindle upwardly. One end of a rocking lever 88 pivoted at 88a, bears on the upper end of spindle 87a while the other end of the lever bears on the upper end of a vertically movable lifter rod 89, the lower end of which is adapted to engage a cam 90 on cam drum 91 carried by the main pattern shaft 57. When the lifter rod 89 rides up on the cam 90, the cam block 87 carried by spindle 87a will be moved downwardly and the inclined surfaces of cam block 87 will engage the transverse pin 85b to move upper shunt cam 85 radially outwardly to inoperative position.

Instead of operating on the knitting butts 33 of the upper sliders 31, the upper shunt cam 75 may act on the transfer butts 32 as illustrated in

the alternative arrangement shown in Fig. 15a. The shunt cam in this figure is indicated by the numeral 85'. The action and operation of the cam may be the same as heretofore described.

At the second feeding station the upper cam ring 34 is provided with a stitch cam 92 adapted to engage the knitting butts of the sliders to draw the upper cylinder needles upwardly, thereby drawing loops of thread received at the second feed. It will be understood that loops are drawn by the needles only when the latter have been moved downwardly by descending cam 82 to position them at a sufficiently low level to take the thread fed at the second feeding station. When the knitting butts of the sliders are by-passed through upper race-way 84, the needles will not take the second thread and will retain previously drawn stitches of thread received at the main feeding station. The stitch cam 92 is preferably vertically adjustable to regulate the amount of thread drawn by the needles at the second feed. Beyond the stitch cam 92, there is provided a welt or clearing cam 93.

The upper cam ring is also provided with a transfer cam 94, adapted to engage transfer butts of upper cylinder sliders to transfer needles from the upper to the lower cylinder. The upper transfer cam 94 is located slightly beyond the lower transfer cam 76 in the direction of travel of the needles in order that all or certain of the needles transferred to the upper cylinder by cam 76 may be retransferred to the lower cylinder before reaching the main feeding station. Cam 94 is at such height that the transfer butts of the upper cylinder sliders will pass above it as illustrated in Fig. 15, unless the sliders are slightly depressed before reaching the transfer cam. It is the function of the selectors 43 to depress selected ones of the upper cylinder sliders to cause corresponding needles to be transferred to the lower cylinder by transfer cam 94 while other needles remain in the upper cylinder. In some instances there may be provided an auxiliary transfer cam 95 (Fig. 15) which is radially movable into and out of operative position and is adapted to engage the transfer butts of all or certain of the sliders to depress them sufficiently to be engaged by transfer cam 94. Suitable mechanism is provided for moving the auxiliary transfer cam into and out of operative position.

Mechanism for actuating the selectors 43 is illustrated in Figs. 1 and 4 to 18. At each of the levels corresponding to the levels of selector butts 43 there is provided a selector lever 100 having a cam incline 100a (Figs. 4 and 5) adapted to engage selector butts disposed at a corresponding level to move associated selectors downwardly. A leveling cam 101 (Fig. 15) located slightly in advance of the selector levers 100 engages leveling butts 43a to position all of the selectors at the proper level for engagement of the selector levers with the selector butts. Each of the selector levers 100 is pivoted on a vertical shaft 102 and the end of the selector lever opposite the cam incline 100a is bifurcated to provide a heel portion 100b and a toe portion 100c. A leaf spring 103 engages the heel portion 100b of each selector lever and tends to swing the lever into operative position to engage selector butts of the selectors. Movement of the selector levers 100 to inoperative position is effected by a pattern drum 104 having projections 104a adapted to engage the toe portion 100c of the selector levers to swing the cam inclines of the levers out of the paths of the selector butts. The projections 104a are

preferably in the form of removable pins which may be inserted or removed to give the desired pattern. It will be understood that the projections 104a are arranged at levels corresponding to the levels of the selector levers.

The pattern drum 104 is mounted on a shaft 105 to which step by step rotary movement is imparted by a pawl and ratchet mechanism comprising a ratchet wheel 106 mounted on the shaft 105 and a pawl 107 carried by a pivoted arm 108 adapted to be engaged by a projection 42a carried on the extension 42 of the upper needle cylinder. The pattern drum is moved forward one step each revolution of the cylinder. When the toe portion 100c of a selector lever rides up on one of the projections 104a on the pattern drum, the selector lever is swung to inoperative position. Where there is no projection 104a, the selector lever 100 drops into operative position and engages any selector butts disposed at a corresponding level moving the selectors downwardly to bring the transfer butts 32 of sliders 31 into engagement with transfer cam 94 and thereby effecting the transfer of corresponding needles to the lower cylinder. The needles associated with selectors which have no selector butts disposed at any of the levels corresponding to the levels of selector levers in operative position will remain in the upper cylinder.

A feature of the present invention is the control of the pattern drum in conjunction with the independent control of separate sets of selector levers to maintain one set of levers inoperative, while levers of another set are moved into and out of operative position through successive cycles of operation. It will be understood that a pattern set up on the pattern drum will be repeated each revolution of the drum. For example if every other selector is provided with a selector butt at number one level to transfer alternate needles to the lower cylinder when the number one selector lever is in operative position and if the corresponding row of projections on the pattern drum has one projection missing so as to allow the number one selector lever to drop into operation for one course, then the machine will produce one course of 1×1 rib knitting at that point in each revolution of the pattern drum where there is no projection in the number one level. As a result of this repetition of the pattern, the difficulty has been encountered that if it were attempted, for example, to use one or more of the selector levers to obtain a particular needle selection in making a welt or selvage edge, another lever for making a rib knit top portion of a sock and other selector levers for producing a Links-Links pattern in the leg portion, the needle selections used for the top and anti-ravel edge will recur during the knitting of the leg and destroy the pattern effect desired. This difficulty is overcome in accordance with the present invention by providing means for controlling the pattern drum and independently controlling separate sets of the selector levers. Speaking of sets of selector levers, it will be understood that the division of the levers into sets may be made in any way desired. For example, where there are twelve selector levers, one lever may constitute one set and the other eleven levers the other set, or the division may be two and ten, three and nine, etc. In the arrangement illustrated by way of example in the drawings, the levers are shown as being divided into two separate sets.

However, it will be understood that there may be three or more sets if desired.

The independent control of separate sets of selector levers may be effected by dividing the pattern drum into two or more sections so that one section of the drum may be rotated while another section is held stationary. However, it has been found to be more convenient to rotate the pattern drum as a unit and obtain the independent control by blocking out the levers of one or another set so that they will not be operated by the projections on the pattern drum. In the arrangement shown in the drawings (Figs. 1, 4, 5 and 6) there is provided a bar 109 for blocking one set of selector levers to maintain them in inoperative position and a separate bar 110 for blocking another set of selector levers to maintain them in inoperative position. The upper bar 109 is pivoted to swing about a vertical shaft 111 and is connected by a link 112 to an arm 113 on a vertical shaft 114. At the lower end of the shaft 114 there is provided an arm 115, the outer end of which is adapted to engage a cam 116 on the end face of a drum 117 on the main pattern shaft 57 (Figs. 1 and 4). When the arm 115 rides up on cam 116, the shaft 114 is rotated in a clockwise direction as viewed in Fig. 4, and through link 112, the upper blocking bar 109 being likewise swung in a clockwise direction about its pivot shaft 111, causing the bar to press against the heel portions 100b of certain selector levers 100, thereby swinging the selector levers to inoperative position against the action of spring 103.

The lower blocking bar 110 (Figs. 5 and 6) is likewise pivoted about vertical shaft 111 and has a projecting arm 110a which is engaged by one end of a bell crank lever 118 pivoted to a suitable support at 118a. The other end of bell crank lever 118 is connected to a lifter rod 119, the lower end of which is pivotally connected to the elbow of a bell crank lever 120, one end of which is pivoted to a bracket 121 and the other is adapted to engage a cam 122 on cam drum 56. When the end of bell crank lever 120 rides up on a high portion of cam 122, the lifter rod 119 will be raised, thereby raising the outer end of bell crank lever 118 and rocking the inner end downwardly and outwardly against the arm 110a projecting from bar 110. This will swing the bar 110 in a clockwise direction as viewed in Fig. 5 against the heel portions 100b of certain of the selector levers 100, thereby maintaining the selector levers in inoperative position. In the particular arrangement illustrated in Figs. 4 to 6 the upper bar 109 controls the ten upper selector levers while the lower bar 110 controls the two lower selector levers. However, the number of levers controlled by each bar can be varied at will by varying the relative lengths of the two bars. If it is desired to divide the selector levers into three or more separately controlled sets, a corresponding number of blocking bars may be provided.

When the upper set of selector levers is maintained in inoperative position by the bar 109, the operation of the selectors and hence the transfer of needles from the upper to the lower cylinder is controlled solely by the selector levers of the lower set which may be moved into and out of operative position by arrangement of the projections on pattern drum 104 to give the fabric structure desired. Conversely, when the lower set of selector levers is maintained in inoperative position by bar 110, the operation of the selectors

is controlled solely by the selector levers of the upper set. It is thus possible to produce one section of fabric of a particular structure by using the selector levers of one set and to produce a subsequent section of fabric of different structure by using the selector levers of the other set while maintaining the first set inoperative.

Cooperating with the independent control of separate selector levers there is provided in accordance with my invention means for controlling individual selector levers of a set so that a plurality of sections of fabric of different structure may be produced by selector levers of a single set. This makes it possible to increase the kinds of fabric structure that can be produced by the machine without increasing the number of separately controlled sets of selector levers required. In the embodiment illustrated in the drawings, the control of individual levers of a single set to produce successive sections of different fabric structure is effected by controlling the pattern drum 104 actuating the selector levers. Referring to Figs. 1, 7 and 8, it will be seen that the driving mechanism for the selector pattern drum comprises the ratchet wheel 106 mounted on the shaft 105 of the drum and actuated by pawl 107, pivotally carried by arm 108 which is freely rotatable on shaft 105 and engages a projection 42a on the extension 42 of the needle cylinder so that the selector pattern drum is moved one step forward each revolution of the needle cylinder. To control the operation of the selector pattern drum 104, there is provided a disc 130 mounted on shaft 105 so as to rotate therewith, the disc being preferably located adjacent the ratchet wheel 106. The disc 130 is provided with a plurality of abutments or recesses shown in the form of two notches N' and N2 formed in the periphery of the disc and adapted to receive the nose 131b of indexing lever 131 freely rotatable on the shaft 114 which controls one set of the selector levers as described above, (Figs. 4 and 6). When the lever 131 drops into any of the notches in disc 130, the disc and hence the selector pattern drum are held against rotation. The notch N' is so located that when it is engaged by lever 131 the pattern drum is in proper position for starting each of successive articles produced by the machine. Other notches such as N2 are positioned to stop the pattern drum at predetermined points as described more fully below.

In order to interrupt the driving mechanism of the selector pattern drum when the drum is held against rotation by lever 131, means is provided for stopping the operation of the pawl 107 and ratchet 106. In the embodiment illustrated in the drawings (Figs. 7, 8 and 11) this comprises a blocking lever 132 freely rotatable on shaft 114 and adapted to engage pawl 107 and hold the pawl at the end of its stroke (solid line Fig. 11) against the action of spring 108a thereby holding arm 108 out away from the cylinder extension 41 and preventing its actuation by the projection 42a. The lever 131 has an abutment which is preferably adjustable and is shown in the form of a set screw 131a which abuts blocking lever 132 so that counterclockwise movement of lever 131 is transmitted to lever 132 and conversely clockwise movement of lever 132 is transmitted to indexing lever 131. A spring 132a extending between blocking lever 132 and a stationary post 133 tends to swing lever 132 and hence also lever 131. When the indexing lever 131 drops into one of the notches in disc 130 under the action of the spring, the blocking lever 132 is swung into

a position (solid line Fig. 11) to block the action of the pawl and ratchet. When lever 131 is swung in a counterclockwise direction to release it from the notch, lever 132 is swung in a counterclockwise direction to the position shown in dotted lines in Fig. 11, permitting the pawl and ratchet to operate to rotate the pattern drum. It will be understood that after the pattern drum has been released, lever 131 will ride along the periphery of disc 130 and will drop into the first notch presented, stopping the rotation of the drum at a predetermined point determined by the position of the notch. The mechanism for interrupting the rotation of the drum 104 is thus controlled by the rotation of the drum itself. The pattern drum is held in indexed position until released by the withdrawal of indexing lever 131 and blocking lever 132.

The release of the selector pattern drum 104 is controlled by the main pattern mechanism of the machine and also by the means for independently controlling separate sets of selector levers (Figs. 4 and 6). In the embodiment illustrated a bell crank lever 134 (Figs. 9 and 14) pivotally mounted at 134c on a stationary bracket 135 has one arm 134a positioned to engage the indexing lever 131 (Fig. 8). The other arm 134b is connected by a link 136 to the elbow of a bell crank lever 137 (Figs. 1 and 9), one end of which is pivoted to bracket 121 and the other end is adapted to engage a cam 138 on the cam drum 56 mounted on the main pattern shaft 57. When the elbow lever 137 rides up on cam 138, the link 136 is raised swinging bell crank lever 134 in a counterclockwise direction (Fig. 14) and thereby swinging indexing lever 131 in a counterclockwise direction (Fig. 8) to release it from a notch in disc 130. It will be understood that through the abutment of set screw 131a the blocking lever 132 is likewise swung in a counterclockwise direction to release pawl 107. The cam 138 need release lever 131 from the notch only a sufficient time to permit the drum to be moved one step by the pawl and ratchet as the lever will then ride on the periphery of disc 130 and will hold lever 132 out of the path of the pawl.

In addition to being controlled by the main pattern drum the release of the selector pattern drum 104 is also controlled by the means controlling independent sets of selector levers. An arm 140 mounted on shaft 114 and rotatable therewith (Fig. 8 and Fig. 13) has an abutment 140a adapted to engage lever 131 and may also have an abutment shown in the form of a set screw 140b adapted to engage lever 132. When shaft 114 is rotated in a counterclockwise direction as occurs when the set of levers controlled by bar 111 (Fig. 6) is released for operation, the arm 140 swings levers 131 and 132 in a counterclockwise direction to the positions shown in dotted lines in Figs. 11 and 12 thereby releasing the selector pattern drum and initiating the racking of the drum by the pawl and ratchet mechanism. The timing of the mechanism controlling the pattern drum will be described below in conjunction with the operation of the machine.

The machine illustrated in the drawings is further provided with means controlled by the main pattern drum for interrupting movement of the selector pattern drum and means controlled by the pattern chain for independently interrupting movement of the selector pattern drum. A lever 141 (Figs. 7, 8 and 10) freely rotatable on shaft 114 is adapted to engage the pawl 107 to hold the pawl and ratchet mechanism out of

operation but is normally held out of the path of the pawl by a spring 142. The tail portion 141a of lever 141 is slotted (Fig. 7) to receive the hooked ends of two Bowden wires 143 and 144. It will be seen that with the arrangement shown either Bowden wire acting independently can pull the lever 141 into operative position to block the pawl 107 without interference by the other Bowden wire. One Bowden wire 143 is connected to a lifter rod 145 (Fig. 1) adapted to engage and be raised by a cam 146 on the main pattern drum 91. When the lifter rod 145 drops off of cam 146 it pulls Bowden wire 143 and swings lever 141 into a position to block the action of pawl 107 (solid lines Fig. 10), thereby interrupting movement of the selector pattern drum 104. It will be understood that if lever 141 is swung into blocking position at any time other than when the pawl is at the end of its stroke (Fig. 11) the spring 107a of pawl 107 permits the pawl to move past lever 141 to the end of its stroke whereupon the tail of the pawl will swing out and engage lever 141.

The lever 141 for interrupting movement of the selector pattern drum is independently actuated by the Bowden wire 144 which is connected to one end of a pivoted lever 147 (Fig. 1) the other end of which is adapted to be engaged by lateral projections on special links of the pattern chain 148. When the lever 147 rides up on a projecting link, one of which is shown at 148a, it pulls the Bowden wire 144 and swings lever 141 into a position to block pawl 107 and stop the pattern drum. The timing of the operation of blocking lever 141 under control of the main pattern drum and the pattern chain will be described below.

The characteristics and capabilities of the machine in accordance with my invention will be more fully understood from the following description of its operation and the fabric structures produced. A characteristic of my machine is that it is capable of producing successive sections of different fabric structures not only by independent control of separate sets of selector levers whereby one set can be employed in producing one section of fabric and another set employed to produce a section of entirely different fabric structure, but also by controlling individual selector levers of a set whereby successive sections of different fabric structure can be produced by levers of the same set. As it will be understood that by reason of its versatility the machine in accordance with my invention is capable of making an infinite number of different patterns or combinations of fabric structure it would be undesirable to attempt to illustrate all of them. However, to assist in describing the operation of the machine, I have shown in Figs. 19 and 20 an article of hosiery exemplifying the combinations of fabric structure that can be produced. The article is shown as having an anti-ravel edge A, a top portion T, a leg portion L, a heel pocket H, a foot F, and a toe pocket P. The production of the anti-ravel edge A shown in the form of a tubular welt, requires a 1 x 1 needle distribution, i. e., alternate needles in the upper cylinder and intervening needles in the lower cylinder. The top portion T is formed of rib knit fabric with wider ribs than 1 x 1 rib knitting and hence requires a needle distribution different from that required for the anti-ravel edge. In the embodiment shown in Fig. 19, the top portion is composed of 2 x 2 rib fabric requiring alternate pairs of needles in the upper cyl-

inder. The top portion T is shown as having an elastic thread E extending coursewise of the fabric, preferably in spaced courses to increase its elasticity and recoverability. The leg portion L formed of Links-Links fabric, i. e., fabric in which individual wales are formed in part of inwardly facing stitches and in part of outwardly facing stitches requiring needles to be transferred from one cylinder to the other in predetermined sequence during the production of successive courses. Moreover, the Links-Links leg portion is provided with a solid color pattern such as diamond D and interrupted vertical stripes formed by prominent solid color stitches V produced by employing a multi-feed machine and by-passing selected needles at least one of the feeds. A section of the fabric of the leg portion is shown in Fig. 20 which represents an enlarged diagrammatic view of the outside of the fabric. In the example shown, alternate courses 1. e., courses c', c3, c5, etc., are formed of a thread t' represented by a heavier line and intervening courses, 1. e., courses c2, c4, c6, etc., are formed of a thread t2, represented by a lighter line. The two threads may be alike, in which case the fabric will have a decorative embossed effect with no color design, or they may differ from one another in material, color, weight or other characteristics. It will be noted that the area D at the left hand side of Fig. 20 is formed of elongated, i. e. double length stitches of thread t' only, the other thread t2 being floated behind such stitches, while the adjacent area B of the fabric is composed of alternate courses of thread t' and thread t2. In a third area at the right hand side of Fig. 20, there are interrupted rows of elongated stitches V of thread t' with thread t2 floated behind them. Assuming for example, that thread t' is red and thread t2 blue, the background area B, together with wales 10, 12 and 14 will be formed of alternate courses of red and blue thread, giving a mixed color effect, while the areas D and the elongated stitches V will be knit of red thread only, providing a solid color red design. Moreover, the background area is formed of inwardly facing stitches, while the design portions D and V are formed of elongated outwardly facing stitches, giving an embossed effect, heightening the design.

In order to produce a Links-Links float thread design of the kind shown in Fig. 20, the transfer butts of the lower cylinder sliders are employed to obtain the selective by-passing of needles at the respective feeds. It is therefore impossible to employ these butts to obtain a 1 x 1 needle distribution for an anti-ravel edge or 1 x 1 rib knit top as has heretofore been the practice, and it is hence necessary to rely on the selector levers and associated mechanisms for controlling all transfer of the needles to obtain the various needle distributions required for the anti-ravel edge, the top portion and the leg portion of the sock. The control of separate sets of selector levers in conjunction with the control of individual levers of a set in accordance with my invention makes it possible to achieve this result.

In the example shown in the drawings, the upper ten selector levers constitute one set and are employed to produce the Links-Links float thread fabric of the leg portion L. As illustrated in Fig. 17, levers 1 to 8 cooperate with selector butts arranged to make the design areas D, while levers 9 and 10 cooperate with selector butts at corresponding levels to produce the elongated stitches V. Selector levers 11 and 12 constitute

another set and are employed to produce both the anti-ravel edge A and the 2 x 2 rib top T. At a level corresponding to selector lever 11, alternate selectors are provided with butts so that when number 11 lever is in operative position, alternate needles are transferred to the lower cylinder and intervening needles remain in the upper cylinder. At a level corresponding to selector lever 12, alternate pairs of selectors are provided with butts so that when number 12 lever is in operative position, the needles are positioned for producing 2 x 2 rib knitting.

The articles of hosiery illustrated in finished form in Fig. 19 are preferably produced by string work, by which is meant that the articles are produced as a continuous string of socks which are thereafter severed from one another and completed by closing the toe pocket. Between successive articles on the string there is a short section of fabric termed a looper's edge which facilitates placing the article on a looping machine to close the toe pocket and is subsequently cut or raveled off. The looper's edge is ordinarily produced by feeding thread at the main knitting station 44 with all of the needles in the lower cylinder to form plain knit fabric. During the knitting of the looper's edge, the selector pattern drum 104 is racked idly around until the indexing lever 131 (Fig. 8) drops into notch N' in disc 130. This orients the selector pattern drum to proper position for starting each of successive articles produced by the machine and the lever 131 holds the drum in this position during the knitting of a plurality of courses of each article. The projections 104a (Figs. 4 and 5) on the pattern drum are so arranged that with the drum in its starting position, selector lever number 11 is permitted to drop into operative position, while selector lever number 12 is held out by a projection on the pattern drum. However, all selector levers are still held out by blocking bars 109 and 110 (Figs. 4 to 6). On the first move of the main pattern drum 91, (Fig. 1) the lower transfer cam 76 (Fig. 15) is moved in to transfer all of the needles to the upper cylinder, and blocking bar 110 (Figs. 5 and 6) is withdrawn to permit the operation of the set of selector levers composed of levers 11 and 12. As lever number 12 is held out by a projection on selector pattern drum 104, only lever 11 drops into operative position and acts on the selector butts at number 11 level (Fig. 15) to retransfer every other needle to the lower cylinder. This results in positioning alternate needles in the upper cylinder and intermediate needles in the lower cylinder. The feeding of thread at the main knitting station is continued so that as soon as the first of the transferred needles reaches the main feeding station, the needles in the upper and lower cylinders will coact to produce 1 x 1 rib knitting. Cam 54 is in operative position, causing the knitting butts of the lower sliders to ride up over the clearing cam 52, while shunt cam 85 is in inoperative position, allowing the knitting butts of the upper sliders to be by-passed through race-way 84, these cams having been moved to their respective positions during the knitting of the preceding sock. At any time after the first of the transferred needles reaches the second feeding station cam 73 is moved in against the ends of the short knitting butts of the lower sliders and picks up the first of the long knitting butts whereupon the cam completes its movement into operative position. The knitting butts of the lower sliders will now ride down the face of cam 73 and under

stitch cam 74. As the first of the knitting butts engage draw down cam 73, a draw thread feed finger is moved into operative position at the second feeding station. By referring to Fig. 15 it will be seen that whereas the thread at the main feeding station is fed to and knit by the needles of both cylinders, the draw thread fed at the second knitting station is received and knit by lower cylinder needles only, the upper cylinder needles being by-passed at a higher level, so that they did not take the draw thread, but retained, the stitches drawn at the main feeding station. This results in the draw thread being knit, at alternate needles only of the fabric. Any desired number of draw thread courses may be produced, but one and a half courses will ordinarily be sufficient. Thereupon the draw thread feed finger is withdrawn. At about the same time the lower transfer cam 76 is also withdrawn.

On the next move of the main pattern drum, the welt or clearing cam 93 is withdrawn and the leveling cam 101 is raised up so that the knitting butts of the upper sliders pass through raceways 84' and 84, carrying the upper cylinder needles high so that they do not knit but hold their stitches. The thread fed at the main feeding station is thus taken and knit by the lower cylinder needles only to produce a plurality of welt courses. After a sufficient number of such courses have been knit, the welt cam 93 is moved to operative position and the leveling cam 101 is brought down, causing the upper cylinder needles to again knit, thereby tying in the previously held stitches and completing the tubular welt.

Several courses before the welt is completed, the main pattern drum is moved to cause lever 137 (Fig. 1) to ride up on cam 138 actuating lever 134 to swing indexing lever 131 out of the notch N' and at the same time swinging blocking lever 132 out of engagement with the pawl 107. The selector pattern drum 104 is thereby released and again starts racking. The selector pattern drum will continue to rack one step forward each revolution of the needle cylinders until the notch N2 in disc 130 is brought into registry with lever 131 which dropped into the notch and thereby stopped the drum. The timing is such that lever 131 reaches the notch N2 at, or shortly after the completion of the welt. The projections 104a in the selector pattern drum are arranged to hold selector lever 12 out of operation and lever 11 in operation while the drum is stationary at notch N' and during all but the last of the moves between notches N' and N2. On the last move, as the notch N2 reaches lever 131, a projection 104a on the selector pattern drum 104 withdraws lever 11 and lever 12 is permitted to drop into operative position.

At approximately the same time that the selector pattern drum reaches and is stopped at the point determined by lever 131 dropping into notch N2, the lower transfer cam 76 is again moved to operative position. This transfers all of the needles to the upper cylinder and every other pair is retransferred by selector lever 12 resulting in positioning alternate pairs of needles in the upper cylinder with intermediate needles in the lower cylinder (Fig. 16) for the production of the 2 x 2 rib top portion T. It will be understood that by different arrangement of the selector butts 43b at number 12 level, any other rib fabric such as 1 x 2 or 2 x 3 rib could be produced. After at least one revolution of the needle cylinder, the lower transfer cam may be withdrawn to save unnecessary transfer of the needles. As the

selector pattern drum 104 is held stationary by indexing lever 131, the 2 x 2 or other needle distribution set up by selector lever 12 will be maintained throughout the knitting of the top. Thus, by reason of the action of indexing lever 131 in holding the selector pattern drum at its initial position during the knitting of a plurality of courses before releasing it, and again stopping the pattern drum at the point determined by the position of notch N2, the pattern drum maintains first selector lever 11 and later selector lever 12 in operative position to maintain the same needle selection during the knitting of a number of courses greater than the number of steps, the pattern drum is moved.

The 2 x 2 rib knit top portion may be produced by either single feed or multi-feed knitting and elastic thread may be incorporated in successive or spaced courses. As illustrated in Fig. 16, fabric thread is fed at the main feeding station 44 to both upper and lower cylinder needles, while elastic thread is fed to upper cylinder needles only at the second feeding station 46, the lower cylinder needles being by-passed at the second feeding station by the withdrawal of shunt cam 54 so that the knitting butts of the lower cylinder sliders pass through race-way 53. With the arrangement shown the descending cam 82 in the upper cam block is so positioned that the upper cylinder needles are not lowered to clearing position after drawing stitches at the main feeding station. Hence, the stitches of fabric thread formed at the main feeding station will be retained in the hooks of the upper cylinder needles and will not be cast off when the needles are drawn up by stitch cam 92 to form loops of the elastic thread thereby drawing off a measured amount of elastic thread from the feed finger 46. After passing the second feeding station, the upper cylinder needles are moved downwardly to clearing position by cam 93, placing the elastic thread received at the second feeding station and the fabric thread received at the main feeding station behind, i. e., above the latches of the needles. When the needles again reach the main feeding station, they draw new loops of the fabric thread casting off the previously drawn loops and dumping the elastic thread on to the web formed by the fact that alternate pairs of stitches of fabric thread are drawn upwardly by the upper cylinder needles while intervening pairs of stitches are drawn downwardly by the lower cylinder needles. Thus, the elastic thread after being measured by being drawn into loops by the upper cylinder needles at the second feeding station is incorporated in the fabric by being laid in between the inwardly facing stitches of fabric thread formed by the upper cylinder needles and the outwardly facing stitches formed by the lower cylinder needles.

If it is desired to produce the top T by multi-feed knitting, fabric thread is fed at both feeding stations and shunt cams 54 and 85 are both in operative position so that both the upper and lower cylinder needles receive and knit the second thread. It will be understood that with this arrangement cam 82 would be positioned to lower the upper cylinder needles to clearing position between the first and second feeds. Elastic thread may be laid in by a suitable feed finger located for example between the two feeds. With two fabric thread feeding stations and a single elastic feed, the elastic thread will automatically be incorporated in spaced, i. e., alternate courses of the fabric.

Upon completion of the top portion T, the set of

selector levers comprising levers 11 and 12 are blocked out of operation by blocking bar 110 (Figs. 5 and 6) and the set comprising selector levers 1 to 10 is released by movement of blocking bar 109 in a counterclockwise direction as viewed in Figs. 4 and 6. By referring to Fig. 4 it will be seen that this movement of bar 109 is accomplished by rotation of shaft 114 in a counterclockwise direction. This rotation of shaft 114 swings arm 140 (Fig. 8) in a counterclockwise direction, withdrawing indexing lever 131 from the notch N2 of disc 130 and also withdrawing blocking lever 132 out of the path of pawl 107 as explained above. The selector pattern drum 104 is thereby released and resumes its step by step movement under the action of pawl 107 and ratchet 106. The projections 104a on pattern drum 104 at levels corresponding to selector levers 1 to 10 are arranged to move these levers into and out of operative position in predetermined sequence to produce the desired links-links fabric of the leg portion L. For example, in Fig. 20 courses c' and c2 (produced simultaneously in two feed work) are knit with selector levers 1 and 9 in operative position, while courses c3 and c4 are knit with selector levers 2 and 10 in operative position. Any desired pattern may be set up by suitable arrangement of the selector butts 43b and the projections 104a on the pattern drum.

To produce the leg portion of the sock shown in Figs. 19 and 20 the upper shunt cam 85 is in operative position and the cam 82 is positioned to lower the needles to clearing position so that the upper cylinder needles will take and separately knit threads fed at the respective feeding stations. Shunt cam 54 is withdrawn permitting the knitting butts of the lower cylinder sliders to pass through race-way 53. However, the passage of knitting butts through this race-way is controlled by selecting cam 63 which is in operative position and is adapted to engage long transfer butts provided on selected ones of the lower cylinder sliders to raise said sliders sufficiently that their knitting butts will ride up the face of clearing cam 52, thereby raising the respective needles to clearing position. Other sliders having shorter transfer butts will not be raised by selector cam 63 and their knitting butts will pass through race-way 53. The needles that are raised by selecting cam 63 and clearing cam 52 to clearing position will take the thread fed at the second feeding station while the needles corresponding to sliders, the knitting butts of which are by-passed through race-way 53 past the feeding station at too low a level to receive the second thread and retain their stitches of the thread received and knit at the main feeding station. It will be observed that draw down cam 73 is in operative position so that the needles that have been raised by cams 63 and 52 will be drawn down by cam 73 and switch cam 74 to draw stitches of the second thread and cast off the previously drawn stitches of the thread knit at the main feeding station. Thus, the thread fed at the main feeding station is received and knit by needles in both cylinders while the thread fed at the second feeding station is received and knit by upper cylinder needles while at least certain lower cylinder needles are by-passed so that they do not receive the second thread. In producing the particular section of fabric shown in Fig. 20, all of the lower cylinder needles are by-passed at the second feed. An infinite number of different effects can be obtained by by-passing selected needles, the selective by-passing of the needles

being controlled by the lengths of the lower transfer butts and the position of selecting cam 63. Where it is desired to knit Links-Links fabric on one side of the needle cylinder and plain knit fabric on the opposite side, as for example in knitting the sole S (Fig. 19) or a plain knit portion H' above the heel, the transfer butts may be made of three different lengths, long and medium butts being provided on one side of the cylinder, i. e., the sole side and long and short butts being provided on the other side of the cylinder, i. e., the instep side.

To produce the plain knit portion H' at the top of the heel, commonly referred to as a high splice, auxiliary transfer cam 95 (Fig. 18) is moved in part way to transfer all of the needles on one side only of the needle cylinder to the lower cylinder and selecting cam 63 is moved in far enough to engage the long and the medium transfer butts. Thus, on one side of the needle cylinder all of the needles are in the lower cylinder and are raised by cam 63 so as to produce two feed plain knitting, while on the other side of the cylinder the needles continue to produce Links-Links fabric, at least certain of the lower cylinder needles, namely those having extra short butts being by-passed at the second feed.

At the beginning of the heel pocket H produced by reciprocation of the needle cylinder, the lifter rod 145 drops off of cam 146 (Fig. 1) pulling on Bowden wire 143 and swinging lever 141 into a position to block pawl 107 (Fig. 10). The selector pattern drum 104 is thereby stopped. Upon completion of the heel pocket, the rod 145 rides up on another section of cam 146, causing lever 141 to swing to a position (Fig. 8) to release the pawl so that the step by step movement of the pattern drum is resumed. The sole portion S is produced in the same manner as the high splice H', the sole being formed of plain knitting and the instep I continuing the Links-Links pattern. If, on completion of the instep I it is desired to produce a plain knit toe band P', the auxiliary transfer cam 95 (Fig. 18) is moved in all the way to transfer all of the needles to the lower cylinder and shunt cam 54 is moved to operative position so that all of the needles will knit at both feeds. Blocking bar 109 (Fig. 6) is swung in a clockwise direction to block out selector levers 1 to 10, levers 11 and 12 being already held out of operation by blocking bar 110. The toe pocket P is produced in the same manner as the heel pocket H and is followed by a looper's edge produced in a manner similar to the toe band P'. During the knitting of the toe band and the looper's edge, the selector pattern drum 104 is racked idly, i. e., without operation of the selector levers since all of the levers are held out of operation by blocking bars 109 and 110 until the indexing lever 131 drops into notch N' of disc 130. This orients the selector pattern drum to proper starting position for the next sock.

As the selector pattern drum has only a limited number of moves and will hence repeat the pattern after a corresponding number of courses, it is sometimes desirable to stop the drum momentarily where two or more courses in a pattern are alike in order to lengthen the pattern. This is accomplished by placing special links 148a in the pattern chain (Fig. 1) with lateral projections adapted to engage lever 147. Actuation of this lever causes Bowden wire 144 to swing the blocking lever 141 into a position to engage pawl 107 and interrupt the movement of the selector pattern drum. As the pattern

chain is customarily moved one-half link each revolution of the needle cylinder, the required number of special links can be inserted in the chain to obtain the results desired.

While reference has been made to a specific article to explain the operation of my machine, it will be understood that by reason of its novel structure and operation the machine is capable of producing an infinite number of different combinations of fabric structure and is in no way limited to the production of the particular article illustrated in the drawings.

What I claim and desire to secure by Letters Patent is:

1. In a circular knitting machine having coaxial superposed needle cylinders, needles transferable from one cylinder to the other and selectors associated with the needles and having selector butts at different levels, the combination of selector levers movable into operative position to act on selector butts of said selectors to transfer selected needles from one needle cylinder to the other, a pattern drum for moving the selector levers into and out of operative position in predetermined order, means for independently controlling separate sets of selector levers to maintain one set of levers inoperative while levers of another set are moved into and out of operative position, driving mechanism for the pattern drum, means for orienting the pattern drum to the proper position for starting each of successive articles produced on the machine and means for stopping the pattern drum at predetermined points during the knitting of each article to maintain the same needle selection for a plurality of courses.

2. In a circular knitting machine having coaxial superposed needle cylinders, needles transferable from one cylinder to the other and selectors associated with the needles and having selector butts at different levels, the combination of selector levers movable into operative position to act on selector butts of said selectors to transfer selected needles from one needle cylinder to the other, a pattern drum for moving the selector levers into and out of operative position in predetermined order, means for independently controlling separate sets of selector levers to maintain one set of levers inoperative while levers of another set are moved into operative position, driving mechanism for the pattern drum, means for orienting the pattern drum to proper position for starting each of successive articles produced and means for holding the pattern drum in said position during the knitting of a plurality of courses at the beginning of each article and thereupon releasing the pattern drum.

3. In a circular knitting machine having coaxial superposed needle cylinders, needles transferable from one cylinder to the other and selectors associated with the needles and having selector butts at different levels, the combination of selector levers arranged at corresponding levels and movable into operative position to act on the selector butts of said selectors, a pattern drum for moving the selector levers into and out of operative position in predetermined order, means for independently controlling separate sets of selector levers to maintain one set of levers inoperative while levers of another set are moved into operative position, driving mechanism for the pattern drum, means for orienting the pattern drum to proper position for starting each of successive articles produced by the machine and holding the pattern drum in said po-

sition during the knitting of a plurality of courses at the beginning of each article and thereupon releasing the pattern drum, and means for interrupting the rotation of the pattern drum after knitting a predetermined number of courses.

4. In a circular knitting machine having coaxial superposed needle cylinders, needles transferable from one cylinder to the other and selectors associated with the needles and having selector butts at different levels, the combination of a plurality of sets of selector levers movable into operative position to act on selector butts of said selectors to transfer selected needles from one needle cylinder to the other, a pattern drum for moving the selector levers into and out of operative position, one set of selector levers being actuated to produce Links-Links fabric and another set comprising a lever for positioning alternate needles in the upper cylinder and a lever for positioning selected needles in the upper cylinder to produce rib knitting other than 1×1 rib, means for independently controlling said separate sets of selector levers to maintain one set of levers inoperative while levers of another set are moved into operative position and means for interrupting movement of the pattern drum to hold an individual selector lever in operative position during the knitting of a plurality of courses.

5. In a circular knitting machine having coaxial superposed needle cylinders, needles transferable from one cylinder to the other and control mechanism comprising a main pattern drum and a pattern chain, the combination of selectors associated with the needles and having selector butts at different levels, selector levers movable into operative position to act on selector butts of said selectors to transfer selected needles from one needle cylinder to the other, a pattern drum for moving the selector levers into and out of operative position, driving mechanism for said selector pattern drum, means controlled by the main pattern drum for interrupting movement of the selector pattern drum and means controlled by the pattern chain for independently interrupting movement of the selector pattern drum.

6. In a circular knitting machine having coaxial superposed needle cylinders, needles transferable from one cylinder to the other and pattern mechanism controlling operation of the machine, the combination of selectors associated with the needles and having selector butts at different levels, selector levers movable into operative position to act on selector butts of said selectors to transfer selected needles from one needle cylinder to the other, a pattern drum for moving the selector levers into and out of operative position, driving mechanism for said selector pattern drum, means for stopping the selector pattern drum in predetermined positions, means for independently holding separate sets of said selector levers out of operative position, means for releasing the selector pattern drum and one set of selector levers and means controlled by the main pattern mechanism for independently releasing the selector pattern drum.

7. In a circular knitting machine having coaxial superposed needle cylinders, needles transferable from one cylinder to the other and pattern mechanism controlling operation of the machine, the combination of selectors associated with the needles and having selector butts at different levels, selector levers movable into op-

erative position to act on selector butts of said selectors to transfer selected needles from one needle cylinder to the other, a pattern drum for moving the selector levers into and out of operative position, means for independently controlling separate sets of selector levers to maintain one set of levers inoperative while levers of another set are moved into operative position, driving mechanism for the selector pattern drum, means for orienting the selector pattern drum to proper starting position for starting each of successive articles produced by the machine, means controlled by the selector pattern drum for interrupting the said drum after knitting a predetermined number of courses and means controlled by the main pattern mechanism of the machine for again initiating movement of the selector pattern drum.

8. In a multi-feed circular knitting machine having coaxial superposed needle cylinders, needles transferable from one cylinder to the other, sliders in each cylinder for actuating the needles and having knitting butts and transfer butts, the combination of means acting on the transfer butts of the lower cylinder sliders for by-passing selected needles at at least one of the feeds, selectors associated with the needles and having selector butts at different levels, selector levers arranged at corresponding levels and movable into operative position to act on selector butts of said selectors to transfer selected needles from one cylinder to the other, means for independently controlling separate sets of selector levers

to maintain one set of levers inoperative while levers of another set are moved into and out of operative position, means for actuating selector levers of one set to produce Links-Links fabric,

5 and means for actuating individual selector levers of another set to position alternate needles in the upper cylinder during the knitting of a plurality of courses and thereafter to position selected needles in the upper and lower cylinders

10 respectively to produce rib knit fabric other than 1 x 1 rib for a plurality of subsequent courses.

9. In a circular knitting machine having coaxial superposed needle cylinders, needles transferable from one cylinder to the other and selectors associated with the needles and having selector butts at different levels, the combination of selector levers movable into operative position to act on selector butts of said selectors to transfer selected needles from one needle cylinder to

15 the other, a pattern drum for moving the selector levers into and out of operative position, mechanism normally operative to move the pattern drum one step forward for each revolution of the needle cylinders, means for maintaining one or more selector levers in operative position

20 to maintain the same needle selection during the knitting of a number of courses greater than the number of steps the pattern drum is moved during the knitting of said courses, and means 25 for holding one or more selector levers inoperative while other selector levers are moved into and out of operative position.

PAUL L. THURSTON.
